CLAIM

The ornamental design for a display terminal as shown and described.

DESCRIPTION

FIG. 1 is a front elevational view of a first embodiment of a display terminal in accordance with my design;

FIG. 2 is a rear elevational view thereof;

FIG. 3 is a top plan view thereof;

FIG. 4 is a left side elevational view thereof;

FIG. 5 is a right side elevational view thereof; and

FIG. 6 is a top, front, right perspective view thereof.

FIG. 7 is a front elevational view of a second embodiment of a display terminal in accordance with my design;

FIG. 8 is a rear elevational view thereof;

FIG. 9 is a top plan view thereof;

FIG. 10 is a left side elevational view thereof;

FIG. 11 is a right side elevational view thereof; and

FIG. 12 is a top, front, right perspective view thereof.

FIG. 13 is a front elevational view of a third embodiment of a display terminal in accordance with my design;

FIG. 14 is a rear elevational view thereof;

FIG. 15 is a top plan view thereof;

FIG. 16 is a left side elevational view thereof;

FIG. 17 is a right side elevational view thereof; and

FIG. 18 is a top, front, right perspective view thereof.

FIG. 19 is an enlarged detail view taken from the indicated area in FIG. 3; and,

FIG. 20 is an enlarged detail view taken from the indicated area in FIG. 9.
